UNITED STATES PATENT OFFICE.

JOHN R. BINGAMAN AND WILLIAM RENNO NAGLE, OF READING, PENNSYLVANIA.

LEGGING.

Application filed March 30, 1926. Serial No. 98,415.

This invention relates to improvements in wearing apparel, and particularly to a novel legging, adapted to entirely cover or almost cover a feminine stocking.

5 Our improved legging may be used as a part of feminine apparel for the protection of the leg from either immediately above or immediately below the knee, down to the foot, and it fits snugly to the upper portion 10 of the foot at the line forming the upper edge of a slipper or pump. The legging will protect the leg against weather conditions and permit the wearing of silk or other thin stockings during winter weather, 15 without ill effects therefrom. The legging is made of specially prepared rubberized artificial or real silk or other cloth, treated to permit it to assume the full fashioned shape of a stocking, and to be a protection 20 at the same time against cold or inclement weather. The legging is artistic in appearance, and constructed so that it will be not only a protection, but will be attractive. The legging is constructed to permit the 25 use of either the so called hookless fastener, or any other suitable fastener, but we prefer to use the hookless fastener as it will facilitate maintaining the meeting edges in perfect alignment. Such fastening will 30 start at the heel and extend to the upper end of the legging, along the vertical center of the back of the legging. When the hookless fastener is employed as part of the present invention, the upper end of the legging 35 is formed by an elastic garter or the like, to permit the same to pass over a high heeled or other shoe, without inconvenience. As the fastener extends from the heel to this garter, it is obvious that substantially the 40 entire back of the legging may be opened.

The invention is illustrated in the accompanying drawing, in which:—

Fig. 1 is a side view of the legging shown on a feminine limb.

45 Fig. 2 is an enlarged side view of the legging with its rear partially open for disclosing the present invention.

Fig. 3 is a sectional view taken on line 3—3 of Fig. 1.

In the drawing, 1 indicates the body of our legging which is formed of rubberized real or artificial silk, or other suitable elastic cloth, and may be of any desired color. The blank or blanks for the body of the legging may be cut from such cloth, and while a 55 single blank may be sufficient, due to the elasticity of the cloth, we prefer to make the legging up from two blanks 2, of the same configuration. Each one of these blanks will form one side of the legging, and these 60 blanks are sewed at the front to form a front seam 3. This seam extends from the top to the toe portion.

Each of the rear edges of the blanks 2, is provided with a fastener strip 4, which 65 is preferably sewed to the blank, and each of these strips carries hookless fasteners 5, at its extreme edge. These hookless fasteners are manipulated by the ordinary operating member 6, which separates the 70 edges when moved in one direction and closes them when moved in the opposite direction. These hookless fasteners extend from the lower edge of each blank to a point adjacent the upper edge of the legging, but not entirely to the top of the legging. The top edges of the blanks are permanently fastened together at the rear so 75 that the upper part of the legging forms a band or circlet, and to enhance the appearance of the legging at this point, we have provided the same with an elastic garter 7, which also functions to draw the upper edge 80 of the legging snugly against the leg and prevent the legging from accidentally dropping down.

85 While it is not absolutely necessary to use the well known hookless fastener, we prefer to use this, as it will maintain a neat joint and facilitate opening and closing the rear 90 of the legging. However, as such hookless fasteners are formed of metal, they are liable to tear or discolor the stocking, and to prevent this, we have provided the rear

edge of one blank with a relatively stiff flap 8, which extends throughout the height of the legging and is sewed in place as indicated at 9. When the legging is in use, this 5 flap will lie between the fasteners and the stocking and consequently will protect the stocking.

As the hookless fasteners will give an unsightly appearance to the rear of the legging, we provide the rear edge of one of the blanks with a strip of fur or other ornamentation 10, which is sewed in place and projects sufficiently to cover the fasteners when the device is in use. Due to 10 this construction, the rear of the legging will have the appearance of a tubular structure with a line of fur up the center of its back. We prefer to attach the flap 8 to one of the blanks 2, and the strip 10 to the other 15 one of the blanks, so as to obtain the overlapping without unsightly bulging.

The lower edge of the legging may be left plain if desired, but the legging is more attractive if the lower edge is provided with 20 a strip of fur 11, which may be sewed to the legging. In some cases, we may place a smaller strip of fur at the upper edge 25 of the legging where the garter 7 is located, and furthermore, we may make the legging 30 sufficiently long to extend above the knee instead of terminating below the knee.

The legging is completed by a strap 12, which is sewed to the lower edges of the blanks 2, and is adapted to engage the instep 35 when the legging is worn.

From the foregoing, it is believed the construction, manner of use, and advantages 40 of the invention may be readily understood, and it is obvious that various changes may be made in the details disclosed, but we desire to call attention particularly to the following novel points:—

The endless upper portion of the legging, due to the hookless fasteners, will snugly fit 45 the leg, and as the material from which the blanks are made is elastic, it is obvious that the legging may be readily drawn over the shoe or up over the knee, if it is made of sufficient length to extend above the knee.

50 The strip of fur or other trimming 10, which hides the line of hookless fasteners, is secured to one edge of the line of opening and projects over the vertical line of fasteners when the latter draws the open edges 55 together, so that this strip effectively conceals the fasteners.

The comparatively stiff flap or stocking 60 protector 8, secured to one edge of the opening and projecting under the edge of the opposite side, when the edges are drawn together, prevents damage to the stocking in moving the member 6 up and down the leg.

Furthermore, the ends of the strap 12 being 65 connected to the sides of the blanks 2, function to hold the front portion of the leg

snugly in place while the operating member 6, is being moved downwardly to close the rear of the legging.

What we claim and desire to secure by Letters Patent is:

1. A legging adapted to extend from a point adjacent the sole of a shoe to a point in the vicinity of the knee, and to be worn over a thin stocking, comprising a body portion opening at the rear only, and this opening extending from the heel to a point in close proximity to the upper end of the legging, the upper end of the legging being provided with an elastic band forming an endless top for the legging, the body of the legging being formed entirely of elastic material to permit the same to stretch, to snugly fit the limb, and means for fastening the rear edges of the legging together. 70

2. A legging comprising a body formed of elastic material opening at its rear only along the central vertical line, the opening extending from the heel to a point in close proximity to the top of the legging, and the top of the legging forming an endless band, 75 fastening means for closing said opening along its entire length, and an ornamental strip secured to one edge of the opening of the legging and arranged to project over the opposite edge of the opening to conceal said 80 fastening means. 90

3. A legging of elastic material provided at its upper edge with an elastic endless band, the rear of the legging opening along a vertical central line, from said band to the lower edge of the legging, fastening elements extending along each edge of the opening, and a relatively stiff flap connected to one edge of the opening and adapted to extend beneath the other edge of the 105 opening to protect the stocking against fastening elements. 100

4. A legging of elastic material of the length to extend over a slipper to a point in the vicinity of the knee, said legging having a strap at its lower end to engage the instep of a slipper, the upper end of the legging being closed by an elastic band, and the rear vertical central line of the legging being open from said band down to the heel, fastening elements for securing the edges of the opening together along the entire edges of the openings, a projecting flap secured to one edge of the opening of the legging and projecting beneath the opposite edge of the opening, and an ornamental strip for concealing said fastening elements. 110 115

5. A legging adapted to be worn over thin hosiery, comprising a body portion of a length to extend from a slipper to a point in the vicinity of the knee of the wearer, said body portion being formed of elastic material and having an endless elastic band at its upper portion to snugly engage the wearer's limb and hold the legging up in position, the 120 125 130

portion of the body below said band being adapted to conform to the configuration of the limb, and the rear of said body portion being split vertically along a central line extending from a point adjacent said band to the lower edge of the legging, the edges of the split being provided with hookless fasteners, a protecting flap secured to one of the rear edges of the body and adapted to extend beneath the other rear edge of the body to protect the stocking from said fastening elements, and an ornamental strip secured to the last mentioned edge of the body and adapted to project over the fastening means for concealing the latter. 15

In testimony whereof we affix our signatures.

JOHN R. BINGAMAN.

WILLIAM RENNO NAGLE.
